UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 19, 1921. Serial No. 470,767.

To all whom it may concern:

Be it known that I, WALTER P. ALBERT, a citizen of the United States of America, residing at East Orange, in the county of Essex, State of New Jersey, have invented certain new and useful Improvements in Telephone-Exchange Systems, of which the following is a full, clear, concise, and exact description.

10 This invention relates to telephone exchange systems and particularly to systems in which machine switches are employed for the extension of connections.

Where a central office in an exchange system is designed to extend calls, which either originate locally or in distant calling offices, both to local called lines in the central office and to outlying called offices, the proper apparatus is provided in the central office for selectively routing the calls to their destination. This apparatus may consist of automatic switches and selecting devices. Moreover, the distant called offices may be provided with selective switches, 25 indicators or other selective apparatus for completing incoming connections or assisting in the completion of such connections to the called lines.

In general, the number of switches in 30 the train needed for the completion of a call will depend upon the capacity of the office containing the called line. This is true where the called line is located in the same office with the switches used to make 35 the selection. Another factor that has a bearing on the number of switches is the capacity of the exchange system or the number of offices in the area to which calls must be made from the central office. The 40 standard practice is to adjust the capacity of all offices such that a given number of switches, say two, an incoming and a final selector, are sufficient. To enable the selection of the desired office, two additional 45 switches are usually provided in the central office, namely, a district and an office selector.

An initiated call, which may originate 50 locally in the central office or, as shown in a present disclosure, may originate in a distant manual office served by an operator, is first extended to the district selector in

the central office. The majority of calls thus originated are destined for lines in distant offices and accordingly the complete 55 designation, consisting of a standard number of digits, is registered on a central office register sender. The sender controls the district selector and office selector to choose a trunk to the proper office and thereafter the incoming and final selectors to 60 select the called line.

There is provided in the central office, however, a limited number of lines which 65 lead to supervisors' desks, complaint operators, information operators and other similar positions. These lines should, of course, be accessible to the subscribers and operators in calling offices. Due to the limited number of such lines in comparison 70 to the capacity of a regular office a single switch, such as a final selector is adequate to make all selections for calls of this nature. The incoming switch is omitted and connections are extended through the district 75 and office selectors directly to the special final switches. This means that the two 80 selections which usually occur at the incoming switch are unnecessary and consequently the corresponding registration in the sender must be taken care of otherwise.

With the foregoing explanation in mind, the present invention has as its object to provide, in a system of this character, means associated with a train of switches for rendering ineffective a portion of the registration on the sender which determines the operation of said switches and which means serves to operate a signal when the switches 85 extend connections to busy lines.

A feature of the invention relates to the provision, in a system where connections are arranged to be extended over a train of switches under the control of a register sender, and where certain connections require only a portion of the switches, of a device associative with the extended connection for rendering ineffective that portion of the designation on the sender pertaining 90 to the eliminated switches and operating a signal when the called line is found busy.

Another feature relates to a device arranged in common to a plurality of final

switches for rendering ineffective a portion of the designation registered in the sender when the switches normally controlled by such portion of the registration are omitted 5 from the connection.

Other features and advantages of the invention will be more clearly understood from a consideration of the following detailed description and from the appended 10 claims.

Referring to the drawing, Figs. 1 to 8 inclusive, when arranged in the order illustrated in Fig. 9, disclose so much of a telephone exchange system as is necessary for 15 a thorough comprehension of the invention.

Fig. 1 shows a subscriber's line terminating before an answering operator's position in an originating office, the operator's cord circuit and a portion of the associated equipment and the outgoing end of a trunk line leading to a distant central switching office.

Fig. 2 shows a district selector switch in the central switching office in which the incoming trunk from the originating manual office terminates.

Fig. 3 illustrates an office selector switch in the central switching office which together with the district selector serves to select trunk lines outgoing to any of the distant 30 offices in the outlying area and also to select trunks leading to local switches in the same office.

Fig. 4 shows a final selector switch in the central switching office where the district and office selectors are located and has access to lines of special character such as those leading to operators' positions. This figure further discloses a switching device arranged in common to all of the final selectors, the function of which will be taken 40 up hereinafter.

Above the broken line in Fig. 5, there is shown in schematic form, the incoming and final selector switches in a distant full mechanical office which is accessible by trunk lines leading from the office selector switches in Fig. 3. Below the horizontal broken line, there is illustrated one of the special lines in the central switching office which leads 50 from the terminal bank of the final selector switch and appears at an operator's position.

Fig. 6 shows the trunk finder switch of a register sender unit which has access to the 55 incoming trunks shown in Fig. 2 for the purpose of associating with any desired one thereof the register sender to which this trunk finder is individual.

Fig. 7 illustrates the counting relay set 60 and controlling sequence switch of the sender.

Fig. 8 shows parts of an operator's keyboard which is common to all of the register senders at her position and also the several 65 registers of the register sending unit shown,

which are arranged to take up their positions in accordance with designations registered on the keyboard.

Description of apparatus.

The automatic selector switches shown in Figs. 2, 3 and 4 are of the well known power driven type in which a plurality of sets of brushes are mounted on a vertical brush shaft arranged to be selectively tripped into engagement with their individual section of the panel terminal bank. The brush shafts are propelled in a vertical direction by means of constantly rotating power drums and which in their upward or setting movement revert impulses to the sender to measure off the distance traversed. In general construction and operation, these switches are all of the same character as the one shown and described in detail in the patent to Craft and Reynolds No. 1,123,-696, issued January 5, 1915. The trunk finder switch 600 illustrated in Fig. 6 is also a panel type power driven switch and differs only from the switches above mentioned as regards certain of its details. For example, only a single set of brushes is mounted on the shaft and is in constant engagement with the terminals of the bank with which they cooperate.

The sequence switches 210, 310, 410, 420, 610 and 710 and also the register sequence switches 800, 810, 820, 830, 840, 850, 860 and 870 are substantially similar in principle and construction to the one described in the patent to Reynolds and Baldwin No. 1,127,-808, issued February 9, 1915. As regards the sequence switches 210, 310, 610 and 710, each of which occurs on a separate sheet of the drawing, it may be noted that all contacts located on the several sheets are controlled by the sequence switches correspondingly situated. In Fig. 4, where two sequence switches appear, the contacts belonging to sequence switch 420 are confined within the area of the small rectangle at the bottom of the sheet, while all remaining contacts on the sheet are a part of sequence switch 410. In Fig. 8, the contacts of the several register sequence switches are segregated by means of the vertical broken lines.

The operator's keyboard which is common to all of the register sender units at her position comprises a plurality of rows of keys upon which she records the office and numerical designation of called lines. The first four registers 800, 810, 820 and 830 are used respectively for controlling the district brush, district group, office brush and office group selections to select trunks leading to the desired office or to local switches and consequently receive that portion of the entire designation which pertains to the called office or the called group of lines. These

registers may be set respectively by means of four different rows of keys, the several keys of each row determining a different setting position for its register. As an alternative, a single row of keys may be provided, each of which when actuated causes all of the four office registers to take up settings characteristic of the particular key. In the drawing, this latter plan is illustrated 10 and two of the office keys 819 and 821 only are shown.

The remaining four registers 840, 850, 860 and 870 correspond to the four digits of the numerical designation and are set respectively by the thousands, hundreds, tens and units keys on the operator's keyboard. These numerical registers in their set position control the sender to determine the incoming brush, incoming group, final brush, 20 tens and units selective movements of the incoming and final switches on calls extended to offices or groups of lines having a capacity necessary to require the use of these two switches.

25 *General description of the system.*

In the system disclosed, it is assumed that the call to be extended over the district selector and office selector 250 and 350 and 30 thence in the proper direction is one which originates in a distant calling office such as the manual office shown in Fig. 1. So far as the invention is concerned, however, it matters not where the call originates 35 whether in a distant office or locally as will be seen hereinafter. The answering operator in the originating office, after being notified by the calling subscriber of the number desired, communicates with the operator in the central switching office by means of an order wire, which is not shown, and requests her to assign an idle trunk for use. The latter operator, who may be termed a cordless operator, assigns the trunk and 40 orally receives from the originating operator the name of the desired office and the number of the called line therein. The cordless operator at the time of assigning the trunk depresses an assigning key 209 which initiates the movement of the trunk 45 finder of an idle register sender unit to associate such unit with the particular trunk taken for use. The cordless operator proceeds to set up the designation communicated to her on the keyboard and the registers in turn take up their settings in accordance with the keys depressed.

If it be assumed that the called line is 60 one belonging to a distant full mechanical office, such as the line 510, the office record on the register sender determines the selective movement of the district selector switch 250 and the office selector switch 350 which choose a trunk line 330-331 outgoing from 65 the central switching office and terminating

in an incoming selector switch at the called office. Thereafter the register sender controls the incoming selector switch 500 and final selector switch 501 in accordance with the designation registered on the numerical 70 registers to complete the connection to the terminals of the called line.

On the other hand, it may be that the desired line is one which leads to an operator's position in the central switching office, such 75 as the position indicated in the lower section of Fig. 5. A call of this character might be one where the calling party wishes to communicate with an information operator, a complaint operator, the supervisor, 80 the trouble man or with the operators at any of the special positions. In this case, the office record on the registers of the sender determines the setting of the district and office switches to route the connection 85 over a trunk leading directly to the final selector switch 460. In order not to necessitate the use of designations having a reduced number of digits for special calls and to avoid confusion on the part of the operator 90 in knowing how many keys on her keyboard to depress the universal number scheme is preserved for these special lines as well as for ordinary lines. Consequently, the register sender when set in accordance with the designation of a line leading to an operator's position has received a full record and is prepared to control both incoming and a final selector, but as the number of the special lines is 95 comparatively small, the incoming switch has been omitted and that part of the designation recorded on the sender which ordinarily determines the incoming brush and incoming group selections is unnecessary. The incoming brush and group registrations 100 are disposed of by means of a sequence switch 420 which is common to all of the final selector switches 460 and which sends back impulses to the sender whenever a connection is extended to one of these final switches to satisfy the incoming registrations. After these registrations have been disposed of the final brush, tens and units 105 selections take place under the control of the sender and the called line is selected. If the called line is found to be busy, the sequence switch 420 again becomes effective 110 and causes the transmission of a busy signal current back to the operator in the originating office to advise her that the connection 115 should be released.

Detailed description of operation.

In considering the detailed operation of the system, it will be first assumed that the subscriber of line 100 wishes to converse 125 with the subscriber of line 510 which belongs to the full mechanical office illustrated in the upper part of Fig. 5. The operator,

in response to the call initiated on the line 100, inserts the plug 101 of the cord circuit 103 in the jack 102 of the calling line and communicates with the subscriber. On 5 learning the designation of the desired line, she converses over the order wire, not shown, with the cordless operator in the central switching office and requests the assignment of an idle trunk for the extension 10 of the connection and also communicates to the cordless operator the name of the office and the number of the called line. The cordless operator, observing that the trunk line 200-201 is not in use at the time, 15 notifies the originating operator of its identity and at the same time depresses her assigning key 209. The actuation of key 209 completes a circuit from battery through the winding of sequence switch 210, the 20 right-hand contact of sequence switch spring 208 (1), contacts of key 209 to ground. Sequence switch 210 energizes and moves out of its normal position and into position 3. In position 3 of sequence switch 25 210, a circuit is established from ground through the lower right-hand contact of sequence switch spring 220 (1+12), upper left-hand contact of said spring (2+17), left-hand armature and back contact of relay 205, right-hand contacts of sequence switch 30 spring 211 (3), conductor 242, right-hand contact of sequence switch spring 634 (1), winding of sequence switch magnet 610 to battery. The sequence switch 610 advances 35 out of position 1 and into position 2.

When sequence switch 610 is in position 2, the trunk finder switch 600 is started in operation to hunt for and find the set of terminals in its bank identifying the assigned 40 trunk 200-201 in order to associate the register sender therewith. The circuit for the up-drive power magnet 615 of the trunk finder switch may be traced from battery through the winding of said magnet, contact 45 of sequence switch spring 604 (2), back contact and left-hand armature of relay 601 to ground. As soon as the brushes 619, 620, 621, 622, and 623 encounter the terminals 624, 625, 626, 627 and 628 individual to the 50 assigned trunk, a circuit is established from battery through the winding of relay 601, left-hand contact of sequence switch spring 603 (2), brush 621, terminal 626, conductor 631, contacts of sequence switch spring 214, 55 closed in position 3, back contact and outer right-hand armature of relay 205, upper left-hand contact of sequence switch spring 222 (2+11), lower left-hand contact of said spring (2+4) to ground. Relay 601 becomes energized, opens the circuit of magnet 615, and completes a holding circuit for 60 itself from battery through the winding of said relay, right-hand contact of sequence switch spring 603 (2+17), right-hand armature and contact of relay 601, brush 619,

terminal 624, conductor 629, lower left-hand contact of sequence switch spring 213 (2 $\frac{3}{4}$ +16), upper right-hand contact of said spring (2+12 $\frac{1}{4}$) to ground. Relay 601 in operating completes a circuit from ground, 70 left-hand armature, front contact, right-hand contact of sequence switch spring 605 (2), winding of sequence switch magnet 610 to battery, driving said sequence switch out of position 2 and into position 6. In 75 position 6 of sequence switch 610, a circuit is closed as follows: ground, through the contact of sequence switch spring 602 (6), brush 620, terminal 625, conductor 630, left-hand contact of sequence switch spring 212 80 (3), right-hand winding of relay 205 to battery. Relay 205 operates and completes a circuit from battery through the winding of sequence switch magnet 210, lower left-hand contact of sequence switch spring 215 85 (1+3), upper right-hand contact of said spring (2+12), front contact and left-hand armature of relay 205, upper left-hand contact of sequence switch spring 220 (2+17), lower right-hand contact of said spring 90 (1+12) to ground. Sequence switch 210 moves out of position 3 and into position 5. The cordless operator in the central 95 switching office having received the name of the called office and the number of the desired line proceeds at once to set up this designation on her keyboard. Assume that the name of the called office is represented by the office key 821 and that the number of the called line 510 is 4 7 3 2. Accordingly, she actuates the office key 821, the No. 4 thousands key 822, the No. 7 hundreds key 823, the No. 3 tens key 824 and the No. 2 units key 825. At the time the sequence 100 switch 610 moves into position 6, a circuit is established for each of the office and numerical registers and these registers commence to rotate. This circuit may be traced from ground through the contact of sequence switch swings 609 (5+6) to conductor 635 105 thence in parallel through the right-hand armatures and back contacts of relays 801, 802, 803, 804, 805, 806, 807, and 808 respectively through the windings of registers 800, 810, 820, 830, 840, 850, 860 and 870 to 110 battery and ground. When the district brush register 800 reaches position 1, a circuit is closed from battery through the winding of relay 801, contact of sequence switch spring 826 (1), left-hand contact of key 821 to ground. Relay 801 operates and opens the circuit of register 800 causing 115 this register to come to rest in position 1. When the district group register 810 reaches position 2, a circuit is closed from battery through the winding of relay 802, contact of sequence switch spring 827 (2), left-hand contacts of office key 821 to ground. Relay 802 operates and opening the circuit 120 of register 810 causes this register to stop 125. 130

in position 2. When the office brush register 820 reaches position 2, a circuit is closed from battery through the windings of relay 803, contact of sequence switch 828 (2) 5 to right-hand contacts of key 821 to ground. Relay 801 operates and stops the register 820 in position 2. As office group register 830 advances to position 4, a circuit is closed from battery through the winding of relay 10 804, right-hand contact of sequence switch spring 829 (4), right-hand contacts of key 821 to ground. Relay 804 becomes energized and arrests the register 830 in position 4. In a similar manner when registers 840, 850, 15 860, and 870 reach positions 4, 7, 3 and 2 respectively, circuits are closed for the relays 805, 806, 807, and 808 through the contacts of sequence switch springs 831, 832, 833, and 834 and the respective keys 822, 20 823, 824 and 825 to ground. Relays 805, 806, 807 and 808 become energized and the corresponding registers stop in positions 4 and 7, 3 and 2.

After all the registers have taken their 25 settings and the relays 801, 802, 803, etc. are energized, a circuit is closed from ground through the contacts and left-hand armatures of all these relays in series, conductor 846, upper contact of sequence switch 30 spring 606 (6), winding of sequence switch magnet 610 to battery. Sequence switch 610 leaves position 6 and moves into position 10. In positions 7 and 8 of sequence switch 610, a temporary circuit is established 35 from ground through the contact of sequence switch spring 611 (7+8), conductor 636, through the windings of magnets 809, 811, 812, 813, 814, 815, 816 and 817 in parallel to battery. The magnets 809, 811, 40 812, etc. are key release magnets and when energized operate to release all depressed keys on the operator's board.

In position 10 of sequence switch 610, a circuit is established as follows for driving 45 the sender sequence switch 710 out of position 1 to place the sender in condition to control brush selection at the district switch: battery, through the winding of the magnet of sequence switch 710, contact of spring 706.

50 50. (1), contact of spring 607 (10) to ground. With the district sequence switch 210 in position 5, and the sender sequence switch 710 in position 2, the fundamental circuit is closed for district brush selection. This 55 circuit may be followed from battery, through the right-hand winding of relay 205, lower left-hand contact of spring 223 (5), lower right-hand contact of said spring (5+8), conductor 633, terminal 628, brush 623, contact of spring 613 (10), winding of the stepping relay 700, contact and outer left-hand armature of the 0' counting relay 712, right-hand contact of spring 701 (2), contact of spring 702 (2+4) to 60 65 ground. Relay 205 becomes energized in

this circuit and closes a holding circuit for itself from battery through the right-hand winding and contact and inner right-hand armature of said relay, upper left-hand contact of spring 223 (2+12), lower right-hand contact of said spring (5+8) and thence to ground over the fundamental circuit as described. Relay 205 establishes a circuit from battery through the winding of sequence switch magnet 210, lower left-hand contact of sequence switch spring 215 (5), upper right-hand contact of said spring (2+12), front contact and left-hand armature of relay 205 to ground through the contacts of sequence switch spring 220. 70 Sequence switch 210 is driven into position 6 where a circuit is established for the up-drive power magnet 224 to cause the upward movement of the brush shaft 227 for the purpose of selecting the proper set of 80 brushes to be tripped. The circuit of the power magnet 224 may be traced from battery through the winding of said magnet, lower right-hand contact of spring 215 (6), upper right-hand contact of said spring 90 (2+12), front contact and left-hand armature of relay 205, through the contacts of sequence switch spring 220 to ground.

The stepping relay 700 which also operates in the fundamental circuit in series with relay 205, closes a circuit from ground through its armature and contact, lower contact of spring 711 (2), conductor 721, contact of spring 847 (1), conductor 835 and thence to the conductor 719, Fig. 7, 100 armature and back contact of counting relay 714, winding of counting relay 715 to battery.

It may be well to explain at this point 105 that the conductors leading from the contacts of the several register sequence switch springs in Fig. 8, such as the conductor 835, which are shown as terminating in small circles including the different ordinals from 0 to 9, are, in actual practice, connected to 110 the conductors terminating in the similarly labeled circles at the armatures of the counting relays.

Relay 715 becomes energized in the circuit above traced and closes a holding circuit from battery through the winding of relay 715, winding of relay 714, contact and armature of relay 715, contact of spring 705 (2) to ground. Relay 714, however, 115 cannot energize at this time since its winding is shunted by the direct path to ground closed at the armature and contact of stepping relay 700.

As the brush shaft 227 approaches the 120 first brush tripping position, brush 234 encounters a metallic segment of commutator 236 and the following circuit is closed for relay 205: battery to the right-hand winding and contact and inner right-hand armature of said relay, upper left-hand contact 130

of spring 223 (2+12), lower right-hand contact of spring 238 (5 $\frac{3}{4}$ +6), commutator 236, brush 234 to ground. This direct circuit to ground shunts the stepping relay 700 in the fundamental circuit. Relay 700 on deenergization opens the shunt around the winding of counting relay 714 and this relay operates in series with relay 715. Upon the next energization of relay 700 which 10 occurs when the brush 234 engages with the next insulating segment of commutator 236, the stepping circuit is extended by way of conductor 719, armature and front contact of relay 714, right-hand armature and contact of relay 712, winding of relay 713 to battery. Relay 713 becomes operated and closes a circuit for itself and the winding of the counting relay 712. Relay 712 being shunted by the stepping relay 700 does not 15 operate. As the brush shaft 227 reaches the second brush tripping position, brush 234 engages a metallic circuit of commutator 236, the stepping relay 700 is shunted and releases its armature to permit the operation 20 of the 0' counting relay 712. Relay 712 at its outer left-hand armature opens the fundamental circuit and at its inner left-hand armature closes a circuit including the upper contact of spring 703 (2), winding 25 of sequence switch 710 to battery. Sequence switch 710 is driven out of position 2 and into position 4. On leaving position 2, sequence switch 720 opens at the contact of spring 705 the holding circuits of the energized counting relays. As soon, following 30 the opening of the fundamental circuit at the sender, as the brush 234 engages the next insulating segment of commutator 236, relay 205 becomes deenergized and opens the circuit of power magnet 224. The brush shaft 227 comes to rest. Relay 205 also completes the circuit from battery through winding of sequence switch 210, upper contacts of spring 211 (6), back contact and left-hand armature of relay 205, contacts 35 of sequence switch spring 220 to ground. Sequence switch 210 moves out of position 6 and into position 7.

With the district sequence switch 220 in position 7 and sender sequence switch 710 in position 4, the fundamental circuit is again established over the path previously traced and relay 205 becomes operative. Relay 205 locks in the fundamental circuit 40 as before and also closes a circuit from battery through the winding of sequence switch magnet 210, lower left-hand contact of spring 215 (7), upper right-hand contact of said spring (2+12), front contact and left-hand armature of relay 205 to ground through the contacts of sequence switch spring 220. Sequence switch 210 moves out of position 7 and into position 8 and the circuit of the updrive power magnet 224 is 45 again closed through the right-hand con-

tacts of sequence switch spring 215, front contact and left-hand armature of relay 205 and contacts of sequence switch spring 220. A circuit is also closed from battery through the winding of trip magnet 226 upper right-hand contact of spring 220 (7), lower right-hand contact of said spring (1+12) to ground. Trip magnet 226 becomes energized and on the first upward movement of the brush shaft 227 in the group selecting operation, the selected set of brushes 228, 229 and 230 are tripped into engagement with the terminals of the bank. 70

The stepping relay 700 which also operates in the fundamental circuit establishes 80 a circuit from ground through its armature and contact, upper contact of spring 711 (4), conductor 722, contact of sequence switch spring 848 (2), conductor 836 and thence to conductor 720 (Figure 7), armature and back contact of No. 2' counting relay 716, winding of relay 717 to battery. Relay 717 operates but due to the shunt around the winding of relay 716 this counting relay remains inert. In the upward 85 movement of the brush shaft 227, the brush 234 engages a metallic segment or commutator 237 for each group of terminals passed over by the brushes 228, 229 and 230 and a circuit is closed as follows for the relay 205: battery through the right-hand winding and contact and inner right-hand armature of said relay, upper left-hand contact of spring 223 (2+12) upper right-hand contact of spring 238 (7 $\frac{3}{4}$ +8) commutator 237, brush 234 to ground. For each closure and opening of this circuit the stepping relay 700 is deenergized and energized permitting a pair of counting relays to be energized and locked. When finally the 0' relay 90 operates, it opens the fundamental circuit and at its inner left-hand armature and contact closes the circuit including the upper contact of spring 703 (4) for driving the sequence switch 710 out of position 4 and into position 6. The sender sequence switch 710 on leaving position 4 opens the holding circuits of the energized counting relays. As soon after the opening of the fundamental circuit by the relay 712 as brush 234 engages an insulating segment of commutator 237, the holding circuit of relay 205 is 95 opened and this relay becomes deenergized. Relay 205 opens the circuit of power magnet 224 causing brush shaft 227 to cease its upward movement. Relay 205 also establishes a circuit from battery through the winding of sequence switch magnet 210, upper contacts of spring 211, (8), back contact and left-hand armature of relay 205 through the 100 contacts of sequence switch spring 220 to ground. Sequence switch 210 advances out of position 8 and into position 9.

In the position 9 of sequence switch 210, a circuit is immediately closed from battery 105

through the right-hand winding of relay 205, lower left-hand contact of spring 223, (9+9½) upper left-hand contact of spring 238 (9+9½) to ground. Relay 205 becomes operative and locks in a holding circuit, provided the first trunk in the group, upon the terminals 231, 232 and 233 of which the brushes 228, 229 and 230 are now standing, is busy. This holding circuit may 10 be traced from battery through the left-hand winding of relay 205, contact of spring 221 (9+10), front contact and outer right-hand armature of relay 205, upper left-hand contact of spring 222 (2+11), upper right-hand contact of said spring (9+16½) test brush 230, and thence to ground over the busy test terminal 233. As will be explained hereinafter, the busy condition of the trunk is indicated by the presence of a ground potential on the test terminal and an idle trunk is characterized by the absence of potential on the test terminal. Relay 205 on operating, closes a circuit from battery through the winding of sequence switch magnet 210, 25 lower left-hand contact of spring 215 (9), upper right-hand contact of said spring (2+12), front contact and left-hand armature 205 through the contacts of sequence switch spring 220 to ground, advancing sequence switch 210 out of position 9 and into position 10. The brush shaft 227 is again moved upwardly to drive the brushes 228, 229 and 230 over the terminals to the bank to search for an idle trunk. The circuit of 30 the power magnet 224 leads from battery through the winding of said magnet, right-hand contacts of sequence switch spring 215, front contact and left-hand armature of relay 205 and thence to ground through the contacts of sequence switch spring 220. On reaching the test terminal 233 of the first idle trunk, the test brush 230 finds no ground potential thereon and consequently the relay 205 releases its armatures to open the circuit of the power magnet 224. The switch comes to rest and a circuit is closed at the same time from battery through the winding of sequence switch magnet 210, upper contacts of sequence switch spring 211 (10), 45 back contact and left-hand armature of relay 205 through the contacts of sequence switch spring 220 to ground. Sequence switch 210 moves into position 11. The circuits are now prepared for the next 50 selection and the fundamental circuit is established to control the brush selective movement of the office selector 350. This circuit may be traced from battery through the right-hand winding of relay 300 lower left-hand contact of spring 303 (1), left-hand contact of sequence switch spring 301 (1+4) conductor 239, terminal 231, brush 228, lower left-hand contact of spring 238 (11), lower right-hand contact of spring 223 (11), 55 conductor 633, terminal 628, brush 623, contact of spring 613 (10), through the winding of the stepping relay 700, contact and outer left-hand armature of relay 712, contacts of spring 701, (6), contact of sequence switch spring 612 (10), brush 632, terminal 627, 70 conductor 632, lower contact of sequence switch spring 219, brush 229, terminal 232, conductor 240, contact of spring 302 (1+4) to ground. Relay 300 becomes energized and locks in a circuit from battery through its 75 front contact and inner right-hand armature, through its outer right-hand armature and contact, lower right-hand contact of spring 303 (1+4) upper left-hand contact of spring 301 (1+4) and thence as above 80 traced over the fundamental circuit to ground. Relay 300 closes a circuit from battery through the winding of sequence switch magnet 310, lower left-hand contact of spring 307 (1), front contact and left-hand armature of relay 300 to ground driving sequence switch 310 out of position 1 and into position 2. In position 2 of the sequence switch, a circuit is closed for the updrive power magnet 311, traceable from battery 85 through the winding of said magnet, right-hand contacts of spring 308 (2), front contact and left-hand armature of relay 300 to ground. The magnet 311, causes the upward movement of brush shaft 314 to select 90 the proper set of brushes. 95

The stepping relay 700, which also energizes in the fundamental circuit, completes a circuit from ground through its armature and contact, lower contact of spring 709 (6), conductor 723, upper contact of spring 849 (2) conductor 837 and thence to conductor 720 (Figure 7) armature and back contact of counting relay 716, winding of relay 717 to battery. Relay 717 operates 100 and prepares a circuit for itself and relay 716. Relay 716, however, cannot operate due to the shunt around its winding closed through the contact and armature of stepping relay 700. On reaching the first brush tripping position, the shaft 314 advances the brush 318 into engagement with the first metallic segment of commutator 321 and a circuit is closed as follows for relay 300: Battery through the right-hand winding and front contact and inner right-hand armature, and through the outer right-hand armature and contact of said relay, lower right-hand contact of spring 303 (1+4), upper 110 right-hand contact of said spring, (1½+2), commutator 321, brush 318 to ground. This circuit holds the relay 300 energized and shuts out the stepping relay 700 in the fundamental circuit. The relay 700 de-energizes removing the shunt from around the winding of relay 716, permitting this latter relay to operate in series with relay 717. For each brush tripping position passed over a pair of counting relays are 115 similarly operated until finally the 0' count- 120

60 conductor 239, terminal 231, brush 228, lower left-hand contact of spring 238 (11), lower right-hand contact of spring 223 (11), 125 conductor 633, terminal 628, brush 623, contact of spring 613 (10), through the winding of the stepping relay 700, contact and outer left-hand armature of relay 712, contacts of spring 701, (6), contact of sequence switch spring 612 (10), brush 632, terminal 627, 70 conductor 632, lower contact of sequence switch spring 219, brush 229, terminal 232, conductor 240, contact of spring 302 (1+4) to ground. Relay 300 becomes energized and locks in a circuit from battery through its 75 front contact and inner right-hand armature, through its outer right-hand armature and contact, lower right-hand contact of spring 303 (1+4) upper left-hand contact of spring 301 (1+4) and thence as above 80 traced over the fundamental circuit to ground. Relay 300 closes a circuit from battery through the winding of sequence switch magnet 310, lower left-hand contact of spring 307 (1), front contact and left-hand armature of relay 300 to ground driving sequence switch 310 out of position 1 and into position 2. In position 2 of the sequence switch, a circuit is closed for the updrive power magnet 311, traceable from battery 85 through the winding of said magnet, right-hand contacts of spring 308 (2), front contact and left-hand armature of relay 300 to ground. The magnet 311, causes the upward movement of brush shaft 314 to select 90 the proper set of brushes. 95

The stepping relay 700, which also energizes in the fundamental circuit, completes a circuit from ground through its armature and contact, lower contact of spring 709 (6), conductor 723, upper contact of spring 849 (2) conductor 837 and thence to conductor 720 (Figure 7) armature and back contact of counting relay 716, winding of relay 717 to battery. Relay 717 operates 100 and prepares a circuit for itself and relay 716. Relay 716, however, cannot operate due to the shunt around its winding closed through the contact and armature of stepping relay 700. On reaching the first brush tripping position, the shaft 314 advances the brush 318 into engagement with the first metallic segment of commutator 321 and a circuit is closed as follows for relay 300: Battery through the right-hand winding and front contact and inner right-hand armature, and through the outer right-hand armature and contact of said relay, lower right-hand contact of spring 303 (1+4), upper 110 right-hand contact of said spring, (1½+2), commutator 321, brush 318 to ground. This circuit holds the relay 300 energized and shuts out the stepping relay 700 in the fundamental circuit. The relay 700 de-energizes removing the shunt from around the winding of relay 716, permitting this latter relay to operate in series with relay 717. For each brush tripping position passed over a pair of counting relays are 115 similarly operated until finally the 0' count- 120

65 conductor 239, terminal 231, brush 228, lower left-hand contact of spring 238 (11), lower right-hand contact of spring 223 (11), 125 conductor 633, terminal 628, brush 623, contact of spring 613 (10), through the winding of the stepping relay 700, contact and outer left-hand armature of relay 712, contacts of spring 701, (6), contact of sequence switch spring 612 (10), brush 632, terminal 627, 70 conductor 632, lower contact of sequence switch spring 219, brush 229, terminal 232, conductor 240, contact of spring 302 (1+4) to ground. Relay 300 becomes energized and locks in a circuit from battery through its 75 front contact and inner right-hand armature, through its outer right-hand armature and contact, lower right-hand contact of spring 303 (1+4) upper left-hand contact of spring 301 (1+4) and thence as above 80 traced over the fundamental circuit to ground. Relay 300 closes a circuit from battery through the winding of sequence switch magnet 310, lower left-hand contact of spring 307 (1), front contact and left-hand armature of relay 300 to ground driving sequence switch 310 out of position 1 and into position 2. In position 2 of the sequence switch, a circuit is closed for the updrive power magnet 311, traceable from battery 85 through the winding of said magnet, right-hand contacts of spring 308 (2), front contact and left-hand armature of relay 300 to ground. The magnet 311, causes the upward movement of brush shaft 314 to select 90 the proper set of brushes. 95

The stepping relay 700, which also energizes in the fundamental circuit, completes a circuit from ground through its armature and contact, lower contact of spring 709 (6), conductor 723, upper contact of spring 849 (2) conductor 837 and thence to conductor 720 (Figure 7) armature and back contact of counting relay 716, winding of relay 717 to battery. Relay 717 operates 100 and prepares a circuit for itself and relay 716. Relay 716, however, cannot operate due to the shunt around its winding closed through the contact and armature of stepping relay 700. On reaching the first brush tripping position, the shaft 314 advances the brush 318 into engagement with the first metallic segment of commutator 321 and a circuit is closed as follows for relay 300: Battery through the right-hand winding and front contact and inner right-hand armature, and through the outer right-hand armature and contact of said relay, lower right-hand contact of spring 303 (1+4), upper 110 right-hand contact of said spring, (1½+2), commutator 321, brush 318 to ground. This circuit holds the relay 300 energized and shuts out the stepping relay 700 in the fundamental circuit. The relay 700 de-energizes removing the shunt from around the winding of relay 716, permitting this latter relay to operate in series with relay 717. For each brush tripping position passed over a pair of counting relays are 115 similarly operated until finally the 0' count- 120

ing relay 712 becomes energized. The relay 712 opens the fundamental circuit and also closes the above traced circuit for advancing the sender sequence switch 710 out of position 6 and into position 8.

As soon, following the opening of the fundamental circuit at the sender, as the brush 318 moves on to the next insulating segment of commutator 321 the circuit of relay 300 is opened and this relay retracts its armatures to open the circuit of power magnet 311. The relay 300 also establishes a circuit from battery through the winding of sequence switch magnet 310, lower right-hand contact of spring 307 (2) back contact and left-hand armatures of relay 300 to ground, driving said sequence switch out of position 2 and into position 3.

In position 3 of sequence switch 310 and position 8 of sender sequence switch 710, the fundamental circuit is closed as previously traced for controlling group selection at the office switch. Relay 300 operates and locks as above explained and also closes the circuit from battery through the winding of sequence switch magnet 310, lower left-hand contact of spring 307 (3), front contact and left-hand armature of relay 300 to ground. Sequence switch 310 moves out of position 3 and into position 4. The tripping magnet 313 is energized in a circuit from battery through the winding of said magnet, lower left-hand contact of spring 306 (3+7) to ground. The magnet 313 positions the trip rod so as to trip the selected set of brushes on the next upward movement of the shaft 314. In position 4 of sequence switch spring 310, the power magnet 311 is again energized in a circuit from battery through the winding of said magnet, right-hand contacts of sequence switch spring 308, front contact and left-hand armature of relay 300 to ground. The brush shaft 314 is driven upwardly, tripping the selecting brushes 315, 316 and 317 and moving them over the bank in the group selecting operation.

The stepping relay 700 upon energizing in the fundamental circuit establishes a circuit to ground through its armature and contact, upper contact of spring 709 (8), conductor 724, left-hand contact of spring 851 (4), conductor 838 and thence to conductor 730 Figure 7, armature and back contact of relay 731, winding of relay 732 to battery. In the manner already explained relay 732 operates and prepares a circuit for itself and relay 731 but the latter relay being shunted cannot operate at this time. As the brush shaft 314 moves from one group selecting position to another, it closes and opens the following circuit for relay 300 causing the successive deenergization of the stepping relay 700 in the fundamental circuit: battery, through the right-hand wind-

ing, front contact and inner right-hand armature and outer right-hand armature and contact of relay 300, lower right-hand contact of spring 303 (1+4), upper left-hand contact of said spring (3 $\frac{3}{4}$ +4) commutator 70 322, brush 318 to ground. For each shunting of the stepping relay 700, an additional pair of counting relays are energized until finally the zero relays 712 and 713 become energized. The relay 712 on operating, 75 opens the fundamental circuit and also completes the above traced circuit for driving sequence switch 710 out of position 8 and into position 10. In leaving position 8, the sequence switch 710 opens the holding circuits of the energized counting relays. At the time the last or 0' counting relay 712 operates the brushes 315, 316, and 317 have been driven to the desired group of terminals, namely the group in which appear 80 trunks leading to the desired office.

As soon, following the opening of the fundamental circuit by the counting relay 712, as the brush 318 engages the next insulating segment of commutator 322 the holding circuit of relay 300 is opened and this relay becomes deenergized to sever the circuit of power magnet 311, causing the brush shaft 314 to cease its upward movement. Relay 300 at the same time closes a circuit from battery through the winding of sequence switch magnet 310, lower right-hand contact of spring 307 (4) back contact and left-hand armature of relay 300 to ground. Sequence switch 310 advances out 95 of position 4 and into position 5.

Upon reaching position 5, the sequence switch 310 closes a circuit from battery through the left-hand winding of relay 300, left-hand contacts of spring 309 (5+7) to 105 ground. Relay 300 actuates and closes a holding circuit for itself, provided the first trunk in the selected group outgoing to the distant office, upon the terminals of which the brushes 315, 316 and 317 are positioned, is busy. The holding circuit of relay 300 110 may be traced from battery through the right-hand winding and front contact and inner right-hand armature of said relay, outer right-hand armature and contact of said relay, upper left-hand contact of spring 305, (5+18), upper right-hand contact of said spring (5+6 $\frac{1}{4}$), test brush 317 to ground through the test terminal 326 of the first busy trunk. Relay 300 on operating 115 closes a circuit from battery through the winding of sequence switch magnet 310, lower left-hand contact of spring 307, (5) front contact and left-hand armature of relay 300 to ground, driving said sequence switch into position 6. The circuit for the updrive power magnet 311 is now closed as previously traced and the brushes 315, 316 and 317 are driven over the terminals of the group to search for an idle trunk. 120 125 130

When the first idle trunk in the group is reached, there being no ground potential on the test terminal 326, the energizing circuit of relay 300 is opened. This relay remains 5 energized for an instant, by means of the following holding circuit: Battery through the left-hand winding of relay 300, upper left-hand contact of spring 309 (5+7), upper right-hand contact of said spring, (5 $\frac{1}{4}$ +6), commutator 323, brush 319 to ground. With the brushes 315, 316 and 317 accurately centered on the terminals 324, 325 and 326 of the idle trunk, the brush 319 engages an insulating segment of commutator 323 and 10 the holding circuit of relay 300 is opened. Relay 300 releases its armatures, the opening circuit of the power magnet 311 and causing the brush shaft to come to rest. Relay 300 also establishes a circuit from battery 15 through the winding of sequence switch magnet 310, lower right-hand contact of spring 307 (6) back contact and left-hand armature of relay 300 to ground, driving the sequence switch out of position 6 and into position 7. In this position a circuit is 20 closed from battery through the left-hand winding of relay 300 upper left-hand contact of spring 309 (5+7) lower left-hand contact of said spring (7) to ground. Relay 300 actuates and closes a circuit from battery through its right-hand winding and front contact and inner right-hand armature, outer right-hand armature and contact of said relay, upper left-hand contact 25 of spring 305 (5+18), lower left-hand contact of said spring (7+18) conductor 241, terminal 233, brush 230, upper right-hand contact of spring 222 (9+16 $\frac{1}{4}$), lower left-hand armature and said spring (10 $\frac{3}{4}$ +18) 30 to ground. Relay 300 remains energized in this circuit during the conversation period. It will be noted that when sequence switch 210 reached position 10 $\frac{3}{4}$, the circuit from ground just traced was closed through test 35 brush 230 to the test terminal 233. The application of ground potential to the test terminal 233 and its multiples renders the trunk 239, 240 and 241 busy to all other district selector switches. Relay 300, upon 40 operating, closes the circuit from battery through the winding of sequence switch magnet 310, lower left-hand contact of spring 307 (7) front contact and left-hand armature of relay 300 to ground, driving sequence switch 310 into position 8. As sequence switch 310 moved into position 6 $\frac{1}{4}$, 45 a circuit is closed as follows and is maintained until the sequence switch leaves position 8 $\frac{1}{4}$: ground through the upper right-hand contact of spring 306 (6 $\frac{3}{4}$ +8 $\frac{1}{4}$), brush 317 to the test terminal 326 and its multiples before other switches. This ground potential on the multiples 326 identifies the trunk 330, 331 as being busy. The district and 50 office selective switches have thus been posi-

tioned to extend the incoming connection to trunk 330, 331, outgoing from the central switching office to the distant full mechanical office to which the called line 510 belongs. 55

Since a detailed description of the operation of the incoming and final selective switches 500 and 501 is not essential to an understanding of the invention, these switches have been indicated in diagrammatic form. They may be of the power driven full mechanical type, being similar in general construction to the other switches shown in this case and more particularly to the character of the incoming and final selective switches disclosed in detail in the application of F. A. Stearn, filed June 3, 1921, Serial No. 474,702. 60

In the well known manner, the fundamental circuit for controlling the brush selection 65 at the incoming selector switch is established and the brush shaft carrying the brushes 502 and 503 is driven upwardly. At the same time the stepping relay 700 in the fundamental circuit operates and closes a circuit from ground through its armature and contact, upper contact of spring 708 (10), conductor 726, upper contact of spring 852 (4) lower contact of springs 853 (5+9) conductor 842 and thence to conductor 719, Fig. 7, armature and back contact of relay 714, winding of relay 715 to battery. The counting relays are operated and when relay 712 finally becomes energized the fundamental 70 circuit is opened and sequence switch 710 100 is driven into position 12. 105

The fundamental circuit is again closed and the incoming selector 500 operates in its group selecting movement. The stepping relay 700 energizes in the fundamental circuit and closes the circuit from ground through its armature and contact, lower contact of spring 708 (12) conductor 725, upper contact of spring 854 (4), conductor 841 and thence to conductor 720, Figure 110 7, armature and back contact of relay 716, winding of relay 717 to battery. A pair of counting relays are energized for each group of terminals passed over by the incoming selector switch and when finally the relay 712 attracts its armatures, the fundamental circuit is opened and sequence switch 710 moves into position 14. 115

Trunk hunting next occurs at the incoming switch and an idle trunk is chosen leading to the final selector switch 501. A fundamental circuit is established and the final selector switch is operated in its brush selecting movement. The stepping relay 700 which energizes in the fundamental circuit closes a circuit from ground through its armature and contact, lower left-hand contact of spring 707 (14), conductor 729, right-hand contact of spring 855, (7), conductor 843 and thence to conductor 720, 120 125 130

Figure 7, armature and back contact of relay 716, winding of relay 717 to battery. When the proper brush selecting position is reached the 0' counting relay 712 operates and the sender sequence switch 710 advances out of position 14 and into position 15.

The selection of the proper group of ten lines, next takes place and the relay 700 energizing in the fundamental circuit establishes a circuit from ground through its armature and contact, lower right-hand contact of spring 707 (15), conductor 728, left-hand contact of sequence switch spring 856 (3) conductor 844, thence to conductor 733, Figure 7, armature and back contact of relay 734, winding of relay 735 to battery. At the end of the tens selection, the 0' counting relay 712 is operated and sequence switch 710 moves into position 16. The fundamental circuit is closed for units selection and relay 700, closes a circuit from ground through its armature and contact, upper contact of spring 707, (16) conductor 727, right-hand contact of spring 857 (2), conductor 845 and thence through conductor 720, Figure 7, armature and back contact of relay 716, winding of relay 717 to battery. When the brushes 506 and 507 of the final selector switch reach the terminals 508 and 509 of the called line the 0' relay 712 is operated to open the fundamental circuit and to advance the sender sequence switch 710 out of position 16 and into position 17. In the well known manner, the called subscriber's line is tested and if found idle, ringing current is applied to operate the bell at the substation.

Restoration of sender.

All selections having been completed, the register sender is no longer needed and may be restored to its normal condition. The initiation of restoration is effected when the sender sequence switch 710 reaches the position 17. In this position a circuit is closed from battery through the winding of sequence switch magnet 610, lower contact of spring 606 (10) contact of spring 704 (17) to ground. Sequence switch 610 advances out of position 10 and into position 13. A circuit is now established from ground through the contact of spring 602 (13) brush 620, terminal 625, conductor 630, left-hand contact of spring 212, (11), right-hand winding of relay 205 to battery. Relay 205 operates and closes a circuit from battery through the winding of sequence switch magnet 210, lower left-hand contact of spring 215 (11), upper right-hand contact of said spring (2+12), front contact and left-hand armature of relay 205 through the contacts of sequence switch spring 220 to ground. Sequence switch 210 thereupon advances out of position 11 and into position 12, and relay 205 becomes deenergized.

If, at this time the operator in the originating office has inserted plug 104 of her cord circuit in the jack 105 of the assigned trunk 200, 201, or, as soon as she does make the insertion, a circuit is established from battery through the winding of relay 106, sleeve of plug 104, sleeve of jack 105, left-hand low-resistance winding of relay 112, right-hand high-resistance winding of said relay to ground. Due to the high-resistance of the right-hand winding of relay 112, the flow of current is insufficient to operate relay 106. Consequently the lamp 109 is lighted in a circuit from battery through said lamp resistance 108 and thence to ground as traced through the windings of relay 112. Relay 112 also operates and a circuit is established from battery through the contact of spring 216 (18+12), right-hand winding of relay 202, conductor 200, upper right-hand winding of repeating coil 110 windings of the polarized relay 111, lower right-hand winding of repeating coil 110, contact and armature of relay 112, conductor 201, left-hand winding of relay 202, contact of spring 217, (18+12) to ground. The current flowing in this circuit operates relay 202 but is not in the proper direction to cause the energization of the polarized relay 111. Relay 202 in turn closes a circuit of relay 203 which latter relay establishes a circuit from ground through its armature and front contact, right-hand contact of spring 212 (12) right-hand winding of relay 205 to battery. Relay 205 operates and closes a circuit from battery through the winding of sequence switch magnet 210, lower left-hand contact of spring 215 (12), upper right-hand contact of said spring (2+12), front contact and left-hand armature of relay 205 through the contacts of sequence switch spring 220 to ground. The sequence switch 210 moves from position 12 into position 13, which is the talking position.

Sequence switch 210 on leaving position 12 opens at the upper right-hand contact of spring 213, the holding circuit of relay 601. Relay 601 becomes deenergized and closes a circuit from ground through its left-hand armature and back contact, left-hand contact of spring 605 (3+17), winding of sequence switch magnet 610 to ground. Sequence switch 610 advances into position 18 where a circuit is closed for restoring the brush shaft 617 of the trunk selector switch 600. This circuit may be traced from battery through the winding of down-drive magnet 616, contact of spring 614 (18) to ground. In the normal position of the brush shaft 617, a circuit is closed from battery through the winding of sequence switch magnet 610, left-hand contact of spring 634 (18), spring 618 and its normally closed contact to ground. Sequence switch 610

thereupon goes into its normal position and a circuit is closed from battery, through the winding of the sender sequence switch magnet 710, lower contact of spring 703 (17), 5 contact of spring 608 (1) to ground. The sender sequence switch 710 is advanced to its normal position, position 1. The register sender unit has now been restored to its normal 10 may condition ready for use in connection with subsequent calls.

Response of the called subscriber and release of the established connection.

When the called subscriber at substation 15 510 responds, a reversal of current is caused over the talking circuit in the well known manner to permit the energization of the polarized relay 111 in the outgoing end of the trunk circuit 200—211 at the originating 20 office. Relay 111 modifies the circuit of relay 106 by excluding the high resistance right-hand winding of relay 112. The removal of this high resistance increases the current flow sufficiently to cause the energization of the marginal relay 106. Relay 106 in operating closes a shunt circuit as follows around the lamp 109: battery, through the armature and contact of relay 106, resistance 107 and thence through the 25 low resistance, left-hand winding of relay 112 to ground through the contact and armature of relay 111. This shunt circuit causes the extinguishment of lamp 109 and the operator is advised thereby that the called operator 30 has answered.

At the end of the conversation when the called subscriber places his receiver on the switchhook, current over the talking circuit is again reversed, relay 111 deenergized, relay 106 also deenergizes and the supervisory lamp 109 is illuminated. The originating operator removes the plug 104 of her cord circuit from the jack 105 of the outgoing trunk causing the deenergization of relay 40 112. Relay 112 at its armature and contact opens the circuit of relay 202 which in turn releases the relay 203. Relay 203 closes a circuit from ground through its armature and back contact of spring 243 (13), lamp 45 206, to battery. The lamp 206 is lighted and notifies the cordless operator at the machine switching office that the connection is no longer required and should be released. She thereupon actuates her disconnect key 50 244 closing a circuit from ground through the contacts of said key, contacts of spring 245 (12+17), winding of relay 204 to battery. Relay 204 completes a circuit from battery through the winding of sequence switch magnet 210, contact of spring 246 55 (12+17), contact and armature of relay 204 through the contacts of sequence switch spring 207 to ground. Sequence switch 210 leaves position 13 and moves into position 60 18 where a circuit is established for releas-

ing the brush shaft 227 of the district selector switch 250. This circuit may be traced from battery through the winding of the down-drive power magnet 225, lower right-hand contact of spring 222 (18), lower 70 left-hand contact of said spring (10 $\frac{1}{2}$ +18) to ground. After the brush shaft has been fully restored to its normal position, a circuit is closed from battery through the winding of sequence switch magnet 210, left-hand contact of spring 208 (7+17), normal position segment 235, brush 234 to ground. Sequence switch 210 by means of this circuit is advanced into position 1.

At the time sequence switch 210 leaves position 16 $\frac{1}{2}$ it opens, at the upper right-hand contact of spring 222, the holding circuit of relay 300. Relay 300 retracts its armatures and a circuit is closed from battery through the winding of sequence switch magnet 310, 85 lower right-hand contact of spring 307 (8+17) back contact and left-hand armature of relay 300 to ground. Sequence switch 310 is driven from position 8 into position 18 where a circuit is established for 90 restoring the brush shaft 314 of the office selector 350. This circuit may be traced from battery through the winding of the down-drive power magnet 312, lower contacts of spring 309 (18) to ground. In the fully 95 restored position of the brush shaft 314, a circuit is closed from battery through the winding of sequence switch magnet 310, upper right-hand contact of spring 307 (3+18), normal position segment 320, brush 100 319 to ground. By means of this circuit the sequence switch 310 is moved into its position 1 and the circuit of the power magnet 312 is opened.

The opening of the talking circuit serves 105 in the well known manner to bring about a release of the incoming and final selector switches 500 and 501.

Establishment of a connection to a local line 110 in the central switching office.

It will next be considered that the subscriber at substation 100 wishes to establish a talking connection with the line 444—445 which leads to an operator's position in the central switching office. As hereinbefore explained, this line is one of a comparatively small group of lines and consequently the usual incoming selector switch is not required in making the selection. Instead, the district selector 250 and office selector 350 are positioned to select a trunk which leads directly to the final selector switch 460 which has access to all of the special lines. There will be as many of these 115 final selector switches as is necessary to handle calls made into the group of special lines.

The initiation of the call, the response by the originating operator, the assignment of 130

an idle trunk 200—201 by the cordless operator and the operation of the trunk selector switch 600 in response to the depression of assignment key 209 for attaching a register sending unit to the assigned trunk all take place in precisely the same manner as hereinbefore described. Since the line 444—445 leading to the operator's position must be reached through a different group of trunks 10 in the terminal bank of the office selector switch 350 than the group in which trunks 330—331 outgoing to the distant mechanical office, appear, it is necessary to perform a different combination of selections at the 15 district and office selectors 250 and 350. Assume that the designation which governs the settings of the district and office switches to select a trunk having access to the group of special lines is represented by the key 20 819 on the operator's key board and that the identity of the particular called line 444—445 in the group is represented by the No. 4 7 3 2. Accordingly the operator depresses key 819, the No. 4 thousands key 25 822, the No. 7 hundreds key 823, the No. 3 tens key 824 and the No. 2 units key 825. By inspecting the connections of the contacts of key 819 with the contacts of the registers 800, 810, 820 and 830, it will be 30 noted that this key causes the district brush register 800, district group register 810 and the office brush register 820 to take exactly the same settings as key 821 which was used for the call previously considered. The 35 office group register 830, however, is set in position 3 instead of in position 4 as in the former case. This different combination of settings of the district and office registers will determine that a trunk leading to one 40 of the final selector switches 460 will be chosen. For simplicity it has further been assumed that the number identifying the called line 444—445 is the same as the number taken for the called subscriber's line 510 45 in the distant mechanical office and accordingly the numerical register 840, 850, 860 and 870 take the same settings as before.

After all the registers have been positioned in the manner hereinbefore explained, the sequence switch 610 moves from position 6 into position 10 where the previously traced circuit is closed for driving the sender sequence switch 710 into position 2 under the control of the registers and counting relays, district brush selection, district group selection and office brush selection take place precisely as hereinbefore described. At the end of this time, the sequence switch 210 is in position 11, the office selector switch 310 is in position 3 and the sender sequence switch 701 is in position 8. The fundamental circuit is again established for controlling group selection of the office switch 350. Relay 300 operates, locks in the

fundamental circuit and completes a circuit 65 for driving sequence switch 310 into position 4 where the brush shaft 314 is moved upwardly under the control of the up-drive magnet 311. The stepping relay 700, energizing in the fundamental circuit, closes a 70 circuit from ground through its armature and contact, upper contact of sequence switch spring 708, conductor 724, lower contact of sequence switch spring 858 (3), conductor 839, thence to conductor 733, Figure 75 7, armature and back contact of relay 734, winding of relay 735 to battery. Relay 735 operates and prepares a circuit for itself and relay 734.

When the brushes 315, 316 and 317 have 80 been driven to the group of terminals containing the terminals of the trunks leading to the final selector switch 460, the 0' counting relay 712 is operated to open the fundamental circuit and also to complete a circuit for driving the sender sequence switch 710 out of position 8 and into position 10. Following the group selecting operation the sequence switch 310 is advanced into position 6, where trunk hunting ensues. The 90 brushes 315, 316 and 317 are driven into engagement with the terminals 327, 328 and 329 of the first idle trunk in the group which leads to the idle final selector switch 460. Thereafter the sequence switch 310 95 advances into position 8.

Immediately that the trunk 332, 333 and 334 is selected and the sequence switch 310 has reached position 8, a circuit is established as follows: battery, through the winding of relay 400, lower left-hand contact of spring 416 (1+14), upper left-hand contact of said spring, upper left-hand contact of spring 406 (1+10), lower right-hand contact of spring 405 (1+15) resistance 430, 105 conductor 332, terminal 327, brush 215, and thence as previously traced over the fundamental circuit through the winding of the stepping relay 700 and returning to brush 316, terminal 328, conductor 333, resistance 110 432, upper left-hand contact of spring 417 (16+10), upper right-hand contact of said spring (1+15) to ground. Relay 400 becomes energized and closes a holding circuit for itself from battery through the winding and front contact and left-hand armature of said relay, upper left-hand contact of spring 406 (1+10) and thence over the fundamental circuit as traced to ground. Relay 400 in operating completes a circuit from 115 battery through the winding of sequence switch magnet 410, upper right-hand contact of spring 412 (1), front contact and right-hand armature of relay 400 to ground driving sequence switch 410 out of position 120 1 into position 2. Immediately that sequence switch 410 reaches position 1 $\frac{1}{2}$ on its way to position 2, a circuit is closed from 125

battery through the winding of sequence switch magnet 420, contact of spring 421 (1), lower left-hand contact of spring 411 (1+4), lower right-hand contact of said 5 spring (1³+14) to ground. The sequence switch 420 which is common to all of the final selector switches 460, is energized in this circuit and rotates through a complete cycle for the purpose of sending impulses back to the 10 sender to satisfy the registrations recorded on the registers which normally serve to control incoming brush and incoming group selections. During the rotation of sequence switch 420 from position 1 through its complete cycle into position 1 again the upper 15 right-hand contact of sequence switch spring 454 is closed in the successive positions from 2 to 18. At each of these closures, the following circuit is momentarily established: 20 battery, through the winding and front contact and left-hand armature of relay 400, upper left-hand contact of spring 406 (1+10), lower right-hand contact of spring 405 (1+15), resistance 430, contact of sequence switch spring 408 (1³+2), upper 25 right-hand contact of sequence switch spring 454 to ground. This circuit maintains the energization of relay 400 and also shunts the stepping relay 700 at the sender to cause 30 its deenergization in the manner already explained. The successive deenergizations and energizations of the stepping relay 700 causes the operation of the successive pairs of counting relays. When therefore the sequence switch 420 has rotated through a given number of positions, the stepping relay 700 will have operated the number of pairs of counting relays determined by the setting of the registers 840 and 850. The operation 40 of the last or 0' counting relay 712 opens the fundamental circuit and also completes the previously traced circuit for driving the sender sequence switch 710 out of position 10 and into position 12. 45 As soon, following the opening of the fundamental circuit by relay 712, as the sequence switch contact 454 is again opened, the circuit of relay 400 is severed and this relay becomes deenergized. Relay 400 on 50 releasing completes a circuit from battery through the winding of sequence switch magnet 410, upper left-hand contact of sequence switch spring 412 (2), back contact and right-hand armature of relay 400 to ground. Sequence switch 410 moves out of 55 position 2 and into position 3. In position 3 of the sequence switch 410 and position 12 of the sender sequence switch 710, the fundamental circuit is again 60 established as traced and relay 400 becomes energized. Relay 400 closes a locking circuit for itself and also establishes the circuit from battery through the winding of sequence switch magnet 410, upper right-hand 65 contact of spring 412 (3), front contact and right-hand armature of relay 400 to ground driving sequence switch 410 into position 4. Relay 700 also operates and completes a circuit from ground through its armature and contact, lower contact of spring 708 (12), 70 conductor 725, upper contact of spring 854 (4), conductor 841 and thence to conductor 720, Figure 7, armature and back contact of relay 716, winding of relay 717 to battery. Relay 717 operates and prepares a circuit 75 for itself and relay 716. If at this time sequence switch 420 has not completed its first cycle, the remaining positions will be utilized in sending back impulses to the sender to satisfy the registration thereof which normally controls incoming group selection. On the other hand, if the sequence switch has already reached its normal position or if it reaches the end of its first cycle prior to the time the proper number of impulses have been reverted to satisfy incoming group selection, it will be driven through a second cycle by means of the circuit previously traced through the contact of sequence switch spring 402 and the lower contacts of sequence switch 411. With the sequence switch 410 in position 4, successive closures of the sequence switch spring 454 completes the following momentary circuit 80 for relay 400; battery, through the winding and front contact and left-hand armature of said relay, upper left-hand contact of spring 406 (1+10), lower right-hand contact of spring 405 (1+15), resistance 430, contact of spring 408 (3³+4), thence to the upper 85 right-hand contact of sequence switch spring 454 to ground. Each time the contact 454 closes, it causes the shunting of stepping relay 700 at the sender and this relay operates to permit the energization of 90 a pair of counting relays. When finally all counting relays representing the incoming group registration have been energized, the fundamental circuit is opened, and the sender sequence switch 710 is driven out of 95 position 12 and into position 14. As soon, following the opening of the fundamental circuit on the 0' counting relay 712, as the contact 454 is opened, relay 400 becomes deenergized and a circuit is closed 100 from battery through the winding of sequence switch magnet 410, upper left-hand contact of spring 412 (4), back contact and right-hand armature of relay 400 to ground. Sequence switch 410 advances from position 105 4 into position 5. When, following this, the sequence switch 420 reaches position 1, whether at the end of its first or its second cycle, it comes to rest inasmuch as the operating circuit is now opened at the lower 110 left-hand contact of sequence switch spring 411. In position 5 of sequence switch 410, and

in position 14 of sequence switch 710, the fundamental circuit is established for controlling the brush selective movement of final selector switch 460. Relay 400 operates and closes a holding circuit for itself over the path previously traced. Relay 400 also establishes a circuit from battery, through the winding of sequence switch magnet 410, upper right-hand contact of spring 412 (5), front contact and right-hand armature of relay 400 to ground, driving sequence switch 410 out of position 5 and into position 6. In position 6, a circuit is closed for the high speed up-drive power magnet 433 traceable from battery, through the winding of said magnet, right-hand contact of spring 419 (6), upper left-hand contact of spring 415 (5 $\frac{3}{4}$ +6), front contact and right-hand armature of relay 400 to ground. The brush shaft 437 is driven upwardly to select the proper set of brushes.

The stepping relay 700, which also operates in the fundamental circuit, closes the circuit hereinbefore traced, through the contact of register 850 for the No. 2 counting relay 717. As the brush shaft 437 reaches its first brush-tripping position, a circuit is closed from battery through the winding and front contact and left-hand armature of relay 400, upper left-hand contact of spring 406 (1+10), upper right-hand contact of spring 405 (5 $\frac{3}{4}$ +6), commutator 450, brush 448 to ground. This circuit holds the relay 400 operated and shunts the stepping relay 700 causing the energization of relay 716 in series with the relay 717. For each following brush-tripping position, the brush 448 encounters a metallic segment and an additional pair of counting relays are energized and locked. When finally, the 0' counting relay 712 is energized, it opens the fundamental circuit and closes a circuit for driving the sender sequence switch out of position 14 and into position 15. As soon, after the opening of the fundamental circuit at the sender, as the brush 448 encounters an insulating segment of commutator 450, the relay 400 becomes deenergized and opens the circuit of the power magnet 433. Relay 400 also completes a circuit from battery, through the winding of sequence switch magnet 410, the left-hand contact of spring 412 (6), back contact and right-hand armature of relay 400 to ground, driving sequence switch 410 out of position 6 and into position 7. In this position and also in the following position a circuit is established from battery, through the winding of the trip magnet 436, lower right-hand contact of spring 418 (7+8), upper right-hand contact of said spring (1+15) to ground. The trip magnet 436 operates and prepares for the tripping of the selected set of brushes on the next upward movement of the switch.

The fundamental circuit is again completed in position 7 of the sequence switch 410 and relay 400 becomes energized. Relay 400 closes a holding circuit for itself and also completes a circuit from battery through the winding of sequence switch magnet 410, upper right-hand contact of spring 412 (7), front contact and right-hand armature of relay 400 to ground. Sequence switch 410 moves into position 8 where a circuit is closed from battery through the winding of the high speed up-drive power magnet 433, right-hand contact of spring 419 (8), upper left-hand contact of spring 415 (7 $\frac{3}{4}$ +8), front contact and right-hand armature of relay 400 to ground. The brush shaft 437 is driven upwardly and the selected set of brushes 438, 439 and 440 are tripped and moved over the terminals of the bank to select the proper group of lines.

The stepping relay 700 also energizing the fundamental circuit, completes the circuit previously traced from ground, through its armature and contact, through the contact of the register 860, and thence through the winding of the No. 3 counting relay 735. Relay 735 operates and prepares a circuit for itself and relay 734. For each group selecting position passed over by the brushes 438, 439 and 440, the commutator brush 447 engages a metallic segment of the commutator 452 and the following momentary circuit is established for relay 400: battery, through the winding and front contact and left-hand armature of said relay, upper left-hand contact of spring 406 (1+10), lower right-hand contact of said spring (7 $\frac{3}{4}$ +8), commutator 452, brush 447 to ground. This circuit causes the shunting of the stepping relay 700 which permits the successive operation of the counting relays until finally the 0' counting relay 712 becomes energized. Relay 712 opens the fundamental circuit and closes the previously traced circuit for driving the sender sequence switch out of position 15 and into position 16. As soon, after the opening of the fundamental circuit by the counting relay 712, as the commutator brush 447 moves on to an insulating portion of the commutator 452, the relay 400 becomes deenergized and opens the circuit of the power magnet 433 causing the brush shaft to cease its upward movement. Relay 400 also establishes a circuit from battery, through the winding of sequence switch magnet 410, upper left-hand contact of spring 412 (8), back contact and right-hand armature of relay 400 to ground driving said sequence switch out of position 8 and into position 9.

In position 9 of sequence switch 410 and position 16 of sequence switch 710, the fundamental circuit is closed for unit selection and relay 400 operates and locks in the holding circuit hereinbefore described. Re-

lay 400 completes a circuit from battery, winding of sequence switch magnet 410, upper right-hand contact of spring 412 (9), front contact and right-hand armature of relay 400 to ground. Sequence switch 410 moves out of position 9 and into position 10. In this position, a circuit is closed from battery, through the winding of the low speed up-drive power magnet 434, left-hand contact of spring 419 (10), upper left-hand contact of spring 415 (9 $\frac{1}{4}$ +10) front contact and right-hand armature of relay 400 to ground. The low speed power magnet 434 causes the brush shaft 437 to be moved upwardly at a low rate of speed.

The stepping relay 700, upon energizing in series with relay 400, prepares a circuit traceable from ground, through its armature and contact and the contact 857 of register 870 to operate the No. 2 counting relay 717. Relay 717 prepares a circuit for itself and relay 716. For each set of line terminals passed over by the brushes 438, 439, 440, the brush 448 engages a metallic segment of commutator 450 and a circuit is closed from battery, through the winding and front contact and left-hand armature of relay 400, upper left-hand contact of spring 400 (1+10), upper right-hand contact of spring 405 (9 $\frac{1}{4}$ +10), commutator 450, brush 448 to ground. This circuit maintains the energization of relay 400 and shunts the stepping relay 700 in the fundamental circuit. When the brushes 438, 439 and 440 reach the terminals 441, 442, and 443, of the called line the 0' counting relay 712 is operated and opens the fundamental circuit. Relay 712 also completes a circuit for driving sequence switch 710 out of position 16 and into position 17. As soon following the opening of the fundamental circuit at the sender, as the brushes 438, 439, and 440 are accurately centered on the terminals 441, 442 and 443, the brush 448 engages an insulating segment of commutator 450 and relay 400 releases. Relay 400 opens the circuit of the power magnet 434 causing the brush shaft to cease its upward movement. Relay 400 also completes a circuit from battery through the winding of sequence switch magnet 410, upper left-hand contact of spring 412 (10), back contact and right-hand armature of relay 400 to ground driving said sequence switch out of position 10 and into position 11.

A test is now made to determine a busy or idle condition of the line 444, 445 and 446 leading to the operator's position. An idle line is identified by the presence of a full ground potential on the test terminal 443 while the test terminal 443 of the busy line will present a reduced ground potential. Assume in the present case that the selected line is idle. The test circuit may be traced

from battery through the right-hand winding of relay 402, lower left-hand and upper right-hand contacts of spring 414 (11+13), left-hand winding of relay 402, lower contact of spring 429 (11+16 $\frac{1}{2}$), brush 440, terminal 443, conductor 446, through the winding of relay 511 to ground. Due to the full ground potential on terminal 443, sufficient current flows through the winding of relay 402 to cause its energization. Relay 402, upon operating, closes a circuit from battery, through its left-hand armature and front contact, left-hand winding of said relay, lower contact of spring 429 (11+16 $\frac{1}{2}$) brush 440 to the test terminal 443 and also to the multiples of this terminal of other switches. The resistance of this circuit through the left-hand winding of relay 402 is low and therefore reduces the ground potential of the multiples of test terminal 443 to a point where the relays 402 of the other switches cannot operate when a test is made. In this way, the line is rendered non-selectable to other switches. Relay 402 also completes a circuit from ground, through its right-hand armature and front contact, lower left-hand contact of spring 412 (11), winding of sequence switch magnet 410 to battery driving sequence switch 410 out of position 11 and into position 13. In position 13, a circuit is closed from battery through the winding of sequence switch magnet 410, upper left-hand contact of spring 412 (13), back contact and right-hand armature of relay 400 to ground, advancing sequence switch 410 into position 14. In position 14, the relay 400 is energized by means of a circuit from battery, through the winding of said relay, lower left-hand contact of spring 416 (1+14), upper left-hand contact of said spring (14), upper right-hand contact of spring 411 (14+18), lower right-hand contact of said spring (14+14) to ground. Relay 400 completes a circuit from battery through the winding of sequence switch magnet 410, upper right-hand contact of spring 412 (14), front contact and right-hand armature of relay 400 to ground driving sequence switch 410 into position 15. On leaving position 14, sequence switch 410 opens the lower left-hand and upper left-hand contacts of spring 416 but relay 400 remains actuated in a circuit from battery, through the winding of said relay, front contact and left-hand armature of said relay, upper right-hand contact of spring 411 (14+18), upper left-hand contact in said spring (2+18), conductor 334, brush 317, upper right-hand contact of spring 306 (6 $\frac{1}{2}$ +8 $\frac{1}{4}$) to ground.

In position 15 of sequence switch 410, a circuit is closed from battery, through the winding of sequence switch magnet 410, lower left-hand contact of spring 412 (15),

front contact and right-hand armature of relay 402 to ground. Magnet 410 is energized in this circuit and the sequence switch moves into position 16 which is the talking position.

Release of the sender and advance of the district selector switch.

When the sender sequence switch 710 reaches position 17, it moves the sequence switch 610 into position 13, and the sequence switch 210 is advanced out of position 11 and into position 12 in the manner hereinbefore described. If the originating operator has already inserted the plug 104 of her cord circuit 103 in the jack 105 of the trunk, relay 203 is operated and sequence switch 210 moves into position 13. Sequence switch 210 in leaving position 12₁ brings about the restoration of the trunk selector and register sender as previously explained.

Completion of the talking connection to the operator's position.

The relay 511 also operates in the test circuit in series with relay 402. Relay 511 completes a circuit from battery through the right-hand winding of relay 512, normal contacts, at the left-hand armature of relay 513, outer armature of relay 511, conductor 444, terminal 441, brush 438, lower left-hand contact of spring 406, (16), lower left-hand contact of spring 405 (16+17), conductor 332, terminal 327, brush 315, contacts of sequence switch spring 301 (8), conductor 239 and thence over the upper side of the talking circuit through the polarized relay 111 and returning over the lower side of the talking circuit to conductor 240, upper contacts of spring 304 (8), brush 316, terminal 328, conductor 333, upper contact of spring 407 (16) brush 439, terminal 442, conductor 445, inner armature and contact of relay 511, normally closed contacts at the right-hand armature of relay 513, left-hand winding of relay 512 to ground. It will be recalled that when the originating operator first inserted the plug of her cord circuit in the jack 105, a circuit was closed through the contacts 216 and 217 for supplying battery current through the windings of relay 202 and polarized relay 111, the current flow being in such a direction as not to cause the operation of the polarized relay. As the district selector sequence switch 210 leaves position 12, the contacts of sequence switch springs 216 and 217 are opened and current is now supplied to the relays 202 and 111 through the winding of relay 512 in the circuit just traced. The flow of current in this circuit is also in such a direction as not to cause the operation of relay 111. Relay 202, however, does remain energized and in so doing, prevents the illumina-

nation of the disconnect lamp 206 at the cordless operator's position.

Relay 512 closes a circuit for the illumination of lamp 514. When the called operator's attention is attracted by the lighted lamp 514, she responds by inserting the plug 516 of her cord circuit 517 into the jack 515 of the incoming line to which the lamp 514 is individual. The insertion of the plug into the jack completes a circuit from battery, through the winding of relay 513, sleeve of jack 515, sleeve of plug 516 to ground. Relay 513 operates and reverses the direction of flow of current through the windings of relay 512 to the talking conductors 444 and 445. This reversal of current causes the energization of the polarized relay 111 which, in the manner already described, results in the extinguishment of the supervisory signal 109 notifying the operator that the call has been answered.

Release of the established connection.

After conversation has been completed, the calling subscriber 100 replaces his receiver on the switchhook and the called operator withdraws the plug 516 from the jack 515. The removal of the plug from the jack permits the release of the relay 513 which causes the reversal of current over the talking circuit. Relay 111 deenergizes in response to the current reversal and lamp 109 is again illuminated to notify the originating operator that the connection is no longer required. She thereupon proceeds to take down her cord circuit which results in the illumination of the disconnect lamp 206 before the cordless operator. The cordless operator thereupon proceeds to release the district and office switches 250 and 350. When the sequence switch 310 of the office selector leaves position 8₁, it opens at the upper right-hand contact of spring 306 the holding circuit of relay 400. Relay 400 retracts its armatures and a circuit is closed from battery, through the winding of sequence switch magnet 410, upper left-hand contact of spring 412 (16+17), back contact and right-hand armature of relay 400 to ground. Sequence switch 410 moves through position 17 and into position 18 where a circuit is closed from battery through the winding of the down-drive power magnet 435, lower left-hand contact of sequence switch spring 415 (18), lower right-hand contact of said spring (14₄+5₂) to ground. The brush shaft 437 is returned to its normal position under the control of magnet 435 and upon reaching its fully restored position, a circuit is closed from battery through the winding of sequence switch magnet 410, lower right-hand contact of spring 412 (18), normal position segment 451, brush 447 to ground. Sequence switch 410 moves into its normal position 1 and

the circuit of the power magnet 435 is opened at the lower left-hand contact of sequence switch spring 415.

Called line busy.

If at the time the brushes 438, 439 and 5 440 are set on the terminals of the called line, this line is engaged, a reduced ground potential will be present on the test terminal 10 443. Hence, when sequence switch 410 arrives in piston 11 and the test circuit is closed, relay 402 does not receive sufficient current to operate. Therefore, a circuit is 15 closed from battery through the winding of relay 400, lower left-hand contact of spring 416 (1+14), lower right-hand contact of said spring (11+13), contact and armature of relay 401, back contact and right-hand armature of relay 402 to 20 ground driving sequence switch 410 out of position 11 and into position 13. When the sequence switch reaches position 12, and in position 13 a circuit is closed from battery through the right-hand winding of relay 401, lower left-hand contact of spring 25 417 (12+13), upper right-hand contact of said spring (1+15) to ground. Relay 401 attracts its armature and opens the circuit of relay 400 causing this latter relay 30 to become deenergized. The release of relay 400 completes a circuit from battery through the winding of sequence switch magnet 410, upper left-hand contact of sequence switch spring 412 (13), back contact and right-hand armature of relay 400 to ground. Sequence switch 410 moves out 35 of position 13 and into position 14. In this position, the relay 400 is energized over the circuit previously traced and causes the advance of sequence switch 410 into position 15, relay 400 locking over the grounded conductor 384 as previously described. In position 15 of sequence switch 410, a circuit is 40 established from battery through the winding of the down-drive power magnet 435, upper left-hand, lower right-hand contact of spring 414 (15), back contact and right-hand armature of relay 402 to ground. The magnet 434 causes the restoration of the 45 brush shaft 437. On reaching its normal position, the brush shaft 437 moves the brush 447 on to the normal position segment 451 which closes the circuit above traced for driving sequence switch 410 into position 50 17.

Immediately that sequence switch 410 passes into position 17, the common device including sequence switch 420 is rendered effective to produce successive reversals of 55 current over the talking circuit to cause the intermittent operation of the polarized relay 111 at the originating operator's position. A circuit is first closed from battery, through the right-hand winding of relay 60 403, left-hand contact of sequence switch

spring 428 (17+3), assuming sequence switch 420 to be in its normal position, conductor 455, upper right-hand contact of spring 406 (16 $\frac{3}{4}$ +17), lower left-hand contact of spring 405 (16+17), conductor 332, 70 thence over the upper side of the talking circuit through the winding of relay 111 and returning over the lower side of the talking circuit through conductor 333, lower right-hand contact of spring 407 (16 $\frac{3}{4}$ +17), conductor 456, right-hand contact of spring 427 (17+3), left-hand winding of relay 403, upper contact of spring 422 (17+3), winding 423 to ground. It will be noted that the flow of current in this circuit is in such a direction as not to operate the polarized relay 111. When the constantly rotating interrupter 425 closes at its metallic segments, a circuit is established from the tone source 426, through the winding 424 to ground. The current flowing in coil 424 induces a current in the winding 423 and a characteristic tone is transmitted over the line to the calling subscriber's receiver which advises him that the called line is busy. Relay 403 becomes operated in the circuit above traced and completes a circuit for relay 404. Relay 404 closes a circuit from battery through the winding of sequence switch magnet 420, 80 contact of spring 421 (1), contact and armature of relay 404 to ground. The sequence switch 420 leaves position 1 and makes a complete revolution. As sequence switch 420 leaves position 3, it opens the above traced circuit for relay 403 and removes the application of the induced tone current from the line. As sequence switch 420 is passing from position 3 $\frac{1}{2}$ to position 7 $\frac{1}{2}$, a circuit is closed from battery through the right-hand winding of relay 403 left-hand contact of spring 427 (3 $\frac{1}{2}$ +7 $\frac{1}{2}$), conductor 456, lower right-hand contact of spring 407 (16 $\frac{3}{4}$ +17), conductor 333, thence over the lower side of the talking circuit through the winding of relay 111 and thence over the upper side of the talking circuit to conductor 332, lower left-hand contact of spring 405 (16+17), upper right-hand contact of spring 406 (16 $\frac{3}{4}$ +17), conductor 455, right-hand contact of spring 428 (3 $\frac{1}{2}$ +7 $\frac{1}{2}$), left-hand winding of relay 403, lower contact of spring 422 (3 $\frac{1}{2}$ +7 $\frac{1}{2}$) to ground. The current flowing in this circuit is in the opposite direction and consequently, relay 111 is energized 90 to cause the extinguishment of the supervisory lamp 109. As sequence switch 420 leaves position 7 $\frac{1}{2}$, the circuit is opened and relay 111 deenergizes to permit the illumination of lamp 109. In positions 8 to 12 of sequence switch 420, the previously traced circuit is closed through the windings of relay 403 and current flows over the talking circuit in the direction opposite to that required for the energization of relay 111. Therefore, this relay remains deenergized 95 100 105 110 115 120 125 130

and the lamp 109 remains illuminated. An interruption of the tone at the calling subscriber's substation is made in positions 8 to 12 of the sequence switch. While the 5 sequence switch 420 is moving through positions 12½ to 16½ the above traced circuit is again completed and current is applied to the talking circuit in the direction necessary to cause the energization of relay 111. 10 Hence the supervisory lamp 109 is momentarily extinguished. If at the time sequence switch reaches the end of its cycle and passes into position 1, the originating operator has not responded to the flashing 15 signal of lamp 109, relay 403 will be energized and relay 404 will be operated to drive the sequence switch 420 through a second revolution. In this manner, the lamp 109 is alternately illuminated and extinguished to advise the operator that the called 20 line is busy.

As soon as the originating operator withdraws the plug 104 from the jack 105 after having advised the calling subscriber that 25 the connection cannot be obtained, the disconnect lamp burns steadily and the cordless operator operates the disconnect key 224 to release the switches in response to the restoration of the office selector switch. Relay 400 becomes deenergized, as explained, and completes a circuit for driving sequence switch 410 into position 18 where the final selector switch 420 is restored to its normal position. As soon thereafter as the common 30 sequence switch 420 reaches position 1, it comes to rest due to the fact that the circuits of relays 403 and 404 are already 35 opened.

The sequence switch 420 and the associated 40 equipment are common to a plurality of final selectors and consequently, conductors 455 and 456 and the conductor extending from the contact of sequence switch spring 421 are multiplied as indicated to similar elements in the remaining selectors of the group. The several contacts of springs 457 and 458 and those of as many additional springs as are necessary are connected to corresponding springs in the other final 45 switches. The closing periods of these interrupting contacts may be chosen in any desired combination. By such an arrangement a common sequence switch 420 may be operating to send impulses over a plurality of 50 connections at the same time to satisfy the incoming brush and group selections of the corresponding senders. It may also be simultaneously transmitting busy signals over a plurality of different connections.

60 What is claimed is:

1. In a telephone system, a plurality of automatic selective switches, a number of switch controlling mechanisms each including a plurality of variably operable registers, means for setting the registers of 65

one of said mechanisms to establish a registration, means for operating the selective switches in accordance with said registration to extend a connection, a device 70 associable with the extended connection and common to said mechanisms, means controlled by said device for rendering ineffective a portion of said registration, a signal, and means controlled by said device for operating said signal. 75

2. In a telephone system, a plurality of automatic selective switches, a number of switch controlling mechanisms each including a plurality of variably operable registers, means for setting the registers of 80 any one of said mechanisms to establish a registration, means for operating the selective switches in accordance with a portion of said registration to extend a connection, a device associable with the extended connection and common to said mechanisms, means controlled by said device for rendering ineffective the remainder of said registration, a signal, and means controlled by said device for operating said signal. 85

90 3. In a telephone system, a series of selective switches, a switch controlling mechanism including a plurality of variably operable registers, means for setting said registers to establish a registration, means for operating a number of said switches in accordance with a portion of said registration to extend a connection to a particular switch, a device associable with said particular switch, means controlled by 95 said device for rendering ineffective a portion of said registration, means for operating said particular switch in accordance with the remaining portion of the registration to further extend the connection, a signal, and means controlled by said device for operating said signal. 100

105 4. In a telephone system, a series of switches, a switch controlling mechanism including a plurality of variably operable registers, means for setting said registers to establish a registration, means for operating a number of said switches in accordance with a first portion of said registration to extend a connection to a particular 110 switch, a device associable with said particular switch, means controlled by said device for rendering ineffective the intermediate portion of said registration, means for operating the particular switch in accordance with the last portion of said registration to further extend the connection, a signal, and means controlled by said device for operating said signal. 115

120 5. In a telephone system, a plurality of automatic selective switches, a switch controlling mechanism including a plurality of variably operable registers, means for setting said registers to establish a registration, means for operating the selective 125

- switches in accordance with said registration to extend a connection, a switching device associable with the extended connection, means for operating said device through a 5 variable number of cycles, means controlled by said device for rendering ineffective a portion of said registration, a signal, and means controlled by said switching device for operating said signal.
- 10 6. In a telephone system, a plurality of automatic selective switches, a switch controlling mechanism including a plurality of variably operable registers, means for setting said registers to establish a registration, means for operating the selective switches in accordance with said registration to extend a connection, a switching device associable with the extended connection and arranged to be operated through a variable number of cycles, means dependent on the character of said registration for determining the number of cycles through which said device is operated, means controlled by said device for rendering ineffective a portion of said registration, a signal, and means controlled by said device for operating said signal.
- 15 7. In a telephone system, a plurality of automatic selective switches, a number of switch controlling mechanisms each including a plurality of variably operable registers, means for setting the registers of one of said mechanisms to establish a registration, means for operating the selective switches, means for sending impulses corresponding to said registration to determine the extent of movement of said switches to selectively extend a connection, a device associable with the extended connection and common to said mechanisms, means operated by said device for sending impulses to render ineffective a portion of said registration, a signal, and means controlled by said device for operating said signal.
- 20 8. In a telephone system, a plurality of selective switches, a group of selective switches, a switch controlling mechanism including a plurality of variably operable registers, means for setting said registers to establish a registration, means for operating said first selective switches in accordance with said registration to extend a connection to any one of the selective switches of said group, a device common to all the 25 switches of said group and associative with the particular one to which the connection is extended, means controlled by said device for rendering ineffective a portion of said registration, means for operating said last mentioned switch to further extend said connection, a signal, and means controlled by said device for operating said signal.
- 30 9. In a telephone system, a plurality of selective switches, a group of final switches, a called line, a switch controlling mecha-
- nism including a plurality of variably operable registers, means for setting said registers to establish a registration, means for operating said first selective switches in accordance with said registration to extend a connection to any one of said final switches, a device common to all the final switches and associative with the particular one to which the connection is extended, means controlled by said device for rendering ineffective a portion of said registration to extend the connection to the called line, a signal, and means controlled by said device dependent upon the condition of the called line for operating said signal.
- 35 10. In a telephone system, a called line, a train of selective switches comprising a certain number of switches for extending connections to said line, a second called line, a second train of switches comprising a lesser number of switches for extending connections to said second line, a number of switch controlling mechanisms each including a plurality of variably operable registers, means for setting the registers of one of said mechanisms to establish a registration corresponding to the designation of the first called line, said registration consisting of component parts, there being as many component parts as there are selective movements in said first train of switches, means for operating the switches of said first train in accordance with said registration to extend a connection to the first called line, means for setting said registers to establish a second registration corresponding to the designation of the second called line, such registration consisting of as many component parts as there are selective movements in the first train of switches, means for operating the switches of the second train in accordance with said second registration to extend a connection to said second called line, a device associative with said second train of switches and common to all of said mechanisms, means controlled by said device for rendering ineffective certain component parts of said second registration, a signal, and means controlled by said device for operating said signal.
- 40 11. In a telephone system, a called line, a train of selective switches comprising a certain number of switches for extending connections to said line, a second called line, a second train of switches comprising a lesser number of switches for extending connections to said second line, a number of switch controlling mechanisms each including a plurality of variably operable registers, means for setting the registers of any of said mechanisms to establish a registration corresponding to the designation of the first

- called line, said registration consisting of component parts, there being as many component parts as there are selective movements in said first train of switches, means for 5 operating the switches of said first train in accordance with said registration to extend a connection to the first called line, means for setting said registers to establish a second registration corresponding to the designation of the second called line, such registration consisting of as many component parts as there are selective movements in the first train of switches, means for operating the switches of the 10 second train in accordance with said second registration to extend a connection to said second called line, a device associative with said second train of switches and common to all of said mechanisms, means controlled 15 by said device for rendering ineffective the component parts of said second registration which correspond to the omitted selections, a signal, and means controlled by said device for operating said signal.
- 20 12. In a telephone system, a plurality of automatic selective switches, a called line, a switch controlling mechanism including a plurality of variably operable registers, means for setting said registers to establish 25 a registration corresponding to the designation of the called line, means for operating

the selective switches in accordance with said registration to extend a connection to the called line, a device associative with one of said switches, means controlled by said device for rendering ineffective a portion of said registration, a signal, and means operated when the called line is busy for rendering said device effective to operate said signal.

13. In a telephone system, a plurality of 40 automatic selective switches, a called line, a switch controlling mechanism including a plurality of variably operable registers, means for setting said registers to establish a registration corresponding to the designation of the called line, means for operating the selective switch in accordance with said registration to extend a connection to the called line, a device associative with one of said switches, means controlled by said device for rendering ineffective a portion of said registration, a signal, means operated 45 when the called line is busy for rendering said device effective to operate said signal, and means controlled by said device for successively reversing the flow of current over the extended connection to intermittently operate said signal.

In witness whereof I hereunto subscribe my name this 14th day of May, A. D., 1921.

WALTER P. ALBERT.
